UNITED STATES PATENT OFFICE

THEORVALD MADLAND, OF CHICAGO, ILLINOIS, ASSIGNOR TO CAMEL COMPANY, OF CHICAGO, ILLINOIS, A CORPORATION OF ILLINOIS

DOOR ELEVATING CONSTRUCTION

Application filed May 23, 1931. Serial No. 539,539.

This invention relates to door elevating construction.

It is an object of this invention to provide a simple, effective and economical elevating 5 construction for car doors.

A further object is the provision of door elevating construction which may be assembled into a unit and subsequently applied to a door.

With these and other objects, which will become more apparent as the description proceeds, this invention comprises the novel construction and combinations hereinafter described and more particularly pointed out 15 and defined in the appended claims.

In the accompanying drawings

Figure 1 is a partial elevation of a car door to which the elevating construction of the invention is applied, the door being in its normal or lowered position.

Figure 2 is a view similar to Figure 1, the door being shown in elevated position.

Figure 3 is a vertical section taken on line 3-3 of Figure 1.

Figure 4 is a vertical section taken on line 4-4 of Figure 1.

Figure 5 is a horizontal section taken on line 5-5 of Figure 1.

Figure 6 is an elevational detail of a roller 30 housing.

Figure 7 is a top plan view of the roller housing shown in Figure 6.

Referring to the drawings there is disclosed a car door 10 formed in the present illustration of wood and provided with customary metallic binding members 11 and 12 and gusset plates 13 and 14. At the bottom edge of the door there is preferably secured an angle member 15 which, in the position of 35 the door shown in Figure 1 of the drawings, is adapted to seat upon and have frictional engagement with a supporting track 16 secured to a side sill (not shown) by means of brackets 17 shown partially in Figures 3 and 40 4 of the drawings.

To permit sliding movement of the door it is necessary to elevate the door above the track. For the accomplishment of this purpose there is provided a plate member 18 45 which may advantageously be a pressing and

which is secured to the door as by means of bolts 19. The plate member is preferably pressed outwardly as indicated at 20 and 21, and connecting these outwardly pressed portions of the plate is an elongated outwardly 55 pressed portion 22. The door opposite the outwardly pressed portions 20 and 21 is provided with recesses 23 and 24. Seated in each of these recesses is a bracket member 25 extending preferably flush with the inner 60 side of the door and provided with attaching flanges 26, 27 and 28 overlapping the outer side of the door. In the form of the bracket illustrated a backing plate 29 is utilized in order to establish the flush relationship between said bracket and the inner side of the door. It is to be understood, however, that an integral casting may be utilized in place of the separate plate members shown constituting these brackets. Each of the brackets 70 is provided with an opening 30 adapted to function as a bearing member.

The outwardly pressed portions 20 and 21 of the plate member 18 are positioned oppositely from the bracket members 25. Each of the outwardly pressed portions is provided with an opening 31 aligned with the openings 30 provided in the brackets 25 and constituting a bearing portion. The bracket members and the outwardly offset portions 80 20 and 21 of the plate member 18 constitute in effect housings in which roller supports 20 are adapted to be received. Each of these supports constitutes preferably a hollow member comprising the side walls 33 and 34, 85 end walls 35 and 36 and a top wall 37. It will be observed from Figure 3 of the drawings that the bottom of said hollow roller supporting member is open in order to permit projection of a roller therethrough. Extending from the side walls 33 and 34 of said supporting member is a plurality of trunnions 38 and 39 adapted to be journaled in the bearings 30 and 31 provided in the bracket 90 25 and in the outwardly pressed portions 20 and 21 of the plate member. The trunnion 39 provided on the wall 33 of the support member is extended through the outwardly pressed portion of the plate member and provided on its end with a rectangular 95 100

lar projection 40 for a purpose hereinafter set forth. The walls 33 and 34 of each of the support members are provided, additionally, with aligned bearings 41 and 42, in which a pin or axle 43 is adapted to be received and upon which a roller 44 is rotatably mounted in engagement with the supporting track 16. The wall 34 of the support member is additionally provided with a lug 45. It is observed that the trunnions 38 and 39 of each of the support members 32 are positioned in eccentric relation upon said support members and, further, that the pin employed in mounting the rollers in said support members is offset relative to said trunnions. A bar 46 is mounted upon the lugs 45 on said support members and constrains said members for simultaneous movement. These lugs, furthermore, have their outer ends positioned in slots 47 provided in the outwardly pressed portions 20 and 21 of the plate member and by this construction the connecting bar 46 is maintained in proper position and the forward extension of the elevating construction relative to the door is decreased. An operating lever 48 is secured upon one of rectangular portions 40 provided on the trunnion 39 of the supporting member. This lever is restricted in its movement by means of an arcuate member 49 secured to the door, the lever for this purpose being provided with a rearwardly spaced finger 50 which overlaps one side of the arcuate member 49. It is noted that the connecting bar 46 is seated within and protected by the outwardly offset elongated portion 22 formed in the plate member 18. The plate member, additionally, has a pair of track engaging members 51 secured thereto in order to prevent displacement of the lower part of the door relative to the track. The track engaging members of course are provided with openings in alignment with the openings formed in the portions 20 and 21 of the plate in order to permit the extension of the trunnions 39 therethrough.

In the elevating movement of the door the lever 48 is grasped and pulled downwardly. During this downward movement of the lever it is clear that the rollers 44 will be forced tightly against the supporting track 16 and will serve as fulcrums about which the door will be elevated. Thereupon the door may be moved toward open or closed positions. The support members 32, during the elevating movement will, of course, have simultaneous movement because of the connection established between them by means of the projections 45 and the connecting bar 46. When the lever is released the door will automatically, by its own weight, again seat itself in frictional engagement with the track.

It is manifest from the relationship of the elements of the door elevating construction that these elements may be assembled into a

unit which subsequently may be readily applied to the door.

It is to be understood that this invention is not limited by the structural details set forth. It is intended to include all such modifications and changes as are comprehended in the claims appended hereto.

I claim:

1. In combination, a sliding door, a track adapted to frictionally support said door in its lowered position and means for elevating said door for sliding movement comprising a plurality of supports provided with eccentric trunnions journaled to said door, a roller rotatably mounted in each of said supports in offset relationship to said trunnions in engagement with said track and an operating lever secured to one of said supports in offset relation to the axis of rotation of the roller, said supports being connected for simultaneous movement.

2. In combination, a sliding door, a track adapted to frictionally support said door in its lowered position and means for elevating said door for sliding movement comprising a plurality of supports provided with eccentric trunnions journaled to said door, a roller rotatably mounted in each of said supports in offset relationship to said trunnions in engagement with said track and an operating lever, one of said trunnions being extended to provide a hub to which said lever is secured, said supports being connected for simultaneous movement.

3. In combination, a sliding door, a track adapted to frictionally support said door in its lowered position and means for elevating said door for sliding movement comprising a plurality of supports provided with eccentric trunnions journaled to said door, a roller rotatably mounted in each of said supports in offset relationship to said trunnions in engagement with said track and an operating lever secured to one of said supports in offset relation to the axis of rotation of the roller, each of said supports being provided with a lug and a bar connecting said lugs.

4. In combination, a sliding door, a track adapted to frictionally support said door in its lowered position and means for elevating said door for sliding movement comprising a plurality of supports provided with eccentric trunnions journaled to said door, a roller rotatably mounted in each of said supports in offset relationship to said trunnions for engagement with said track and an operating lever secured to one of said supports, each of said supports being provided with a lug, a bar connecting said lugs and a plate secured to said door and provided with an offset portion adapted to receive said bar, said plate being slotted and said lugs extending into said slots.

5. In combination, a sliding door, a track adapted to frictionally support said door in

its normal position, a plurality of roller supports having eccentric trunnions journaled in bearings provided on said door, a roller rotatably carried by each of said supports 5 for engagement with the track, the axis of rotation of each of said rollers being offset relative to said trunnions, means for operating one of said supports to elevate said door and means connecting said supports for 10 simultaneous movement.

6. In combination, a sliding door, provided with a plurality of spaced recesses at the lower margin thereof, a bracket positioned in each of said recesses flush with the 15 inner side of said door having securing flanges overlapping said door and a bearing, a plate member secured to said door and spanning said recesses, said plate member having bearings in alignment with the bearings 20 in said brackets, roller supports having eccentrically positioned trunnions, journaled in said bearings, rollers mounted in said supports upon an axis offset from said trunnions, means connecting said supports for 25 simultaneous movement and means for operating one of said supports.

7. A unit door elevating construction comprising, in combination, a plate member provided with offset portions, a plurality of 30 spaced brackets secured to said plate member opposite said offset portions, roller supports having eccentrically positioned trunnions journaled in bearings provided in said respective brackets and offset portions 35 of the plate member, a roller carried by each of said supports in offset relation to said trunnions, said plate member having an elongated offset portion connecting said first mentioned offset portions, a bar seated in 40 said elongated offset portion and connecting said roller supports for simultaneous operation and an operating lever secured to one of said supports.

8. A unit door elevating construction comprising in combination a plate member provided with offset portions, a plurality of 45 spaced brackets secured to said plate member opposite said offset portions, roller supports having eccentrically positioned trunnions journaled in bearings provided in said 50 respective brackets and offset portions of the plate member, a roller carried by each of said supports in offset relation to said trunnions, a bar connecting said roller supports 55 for simultaneous operation and an operating lever secured to one of said supports.

Signed at Chicago, Illinois, this 19th day of May, 1931.

THORVALD MADLAND.
